FIG. 7

Isaac Snow
INVENTOR.

BY

Gardner D. Pearson
ATTORNEY.

UNITED STATES PATENT OFFICE.

ISAAC SNOW, OF LAWRENCE, MASSACHUSETTS.

SHUTTLE.

Application filed April 14, 1922. Serial No. 552,685.

To all whom it may concern:

Be it known that I, ISAAC SNOW, a citizen of the United States, residing at Lawrence, in the county of Essex and State of Massachusetts, have invented certain new and useful Improvements in Shuttles, of which the following is a specification.

My invention relates to improvements in shuttles of the self-threading type such as 10 are used in weft replenishing looms.

I am familiar with patents issued to myself, No. 1,344,734, June 29, 1920; No. 1,369,306, February 22, 1921; and No. 1,375,187, April 19, 1921, and with the well 15 known Draper type of self-threading shuttles, but these are suitable for what may now be called in the trade the normal or left eye and the normal wind of yarn on the bobbin.

This invention is an improvement the purpose 20 of which is to provide self-threading devices for use in a shuttle with a left eye and reverse wind, or a right eye and normal wind.

For convenience and for the purpose of 25 identification in this specification, I will call the "front" that end of the shuttle where the eye is located, and the other end of the shuttle the "back".

I will call an eye which passes out of the 30 left side when looking at the front point a "left eye", and an eye on the opposite side a "right eye".

I will call the top of the shuttle as it runs in a loom the "top side", and the bottom 35 the "bottom side".

I will call a "reverse wind", one where looking at the top of a bobbin in a shuttle from the front, the yarn has been wound on from left to right in the direction of the 40 hands of a clock and which unwinds in the reverse direction or contra-clockwise.

In all the figures of the drawings I show 45 a shuttle with a "left eye" and a bobbin with a "reverse wind".

In the drawings, Fig. 1 is a plan view of the front end of a shuttle with a metal 50 threading block in which the preferred form of my device is embodied.

Fig. 2 is an elevation from the left of 55 Fig. 1.

Fig. 3 is a view similar to Fig. 2 of a threading block including my device, the shuttle being indicated by dotted lines.

Fig. 4 is a view of the threading block re- 55 moved from the shuttle viewed from the op-

posite side from Fig. 3, i. e. as from the right of Fig. 1, with part broken away.

Fig. 5 is a sectional view on line 5—5 of Fig. 1 from the direction of the arrow.

Fig. 6 is a view from the front of my 60 threading block removed from the shuttle and with the guide hook cut off.

Fig. 7 is a view similar to Fig. 6 showing a slight modification.

S is a shuttle having the usual bobbin 65 chamber 10 for the bobbin B on which the yarn A is wound with a reverse wind as shown in Fig. 1. 12 is the threading chamber which extends forward in continuation of bobbin chamber 10, and 13 is the delivery 70 passage which extends still further forward from the threading chamber. H represents the shuttle eye in the wood and this connects with the threading chamber 12 and delivery passage 13 through the cut away part 75 14. The usual bearing pins 17, 17 are shown.

I show my invention embodied in what I will call a threading block C which may be cut and sawed out of a single casting or may have its various parts welded or otherwise attached together as is most convenient.

The wood of the shuttle about the threading chamber 12 is cut away to receive threading block C which at the bottom has a projection 34 which sets into a suitable recess in the wood of the shuttle and a hole 35 for the retaining bolt or screw 36, both in a well known manner. The wood also encloses a part of the threading chamber 87, as 90 shown in Fig. 5, which is a part of the threading chamber 12 in the wood.

This threading block C is made up of a nose block G and a thread directing guide plate F which is shown as integral therewith but these might be separate pieces united at the dotted line X shown in Fig. 5.

Nose block G is fixed in the threading chamber on the eye side, being part of block C held in place by screw 36. It has a nose 100 37 which curves over and toward the right, extending forward of the eye H and terminating in a tip 38 which curves back to the right. The top of this nose 37 and of tip 38 slopes down to the right to facilitate the 105 yarn A getting into its proper position on the first pick in threading, and the back 39 of tip 38 forms at the back a stop hook which prevents loops of yarn from unthreading if thrown forward.

The thread guide horn 32 extends down and back below the nose 37 in such manner that it will guide the yarn downward against the vertical thread guide pin 33 located behind said horn and about in line with the middle of eye H.

Thread directing guide plate F is also fixed in the threading chamber on the opposite side from the eye H by being part of 10 threading block C held in place by bolt 36.

This slopes from the top side of the shuttle down into the threading chamber in the same direction and proximate the normal unwinding path of the yarn as it unwinds 15 on the first pick of the shuttle in a magazine loom. 23 represents an extreme forward portion from which it slopes down and back to a point 25 and thence along under the nose 37 and 38 of the nose block G to 20 the back part 24 of guide plate F where it is extended to form a thread retaining guide hook from and under the back part thereof. Preferably, the back part 28 and the front part 29 of this hook 24 slope 25 around toward each other so that the yarn cannot catch thereon.

Preferably, directly behind this hook is a recess 84 which holds friction 85 in a position to overlap the bottom part of hook 30 guide 24 thereby serving as a friction and also as a lock.

The guide hook such as 24 may be more or less involute, as shown in my Patent No. 1,375,187 mentioned above or as shown in 35 Figs. 5 and 6 of the drawing, or it may be merely a hook or finger with a very slight curve, as shown in Fig. 7 at 124. It may pass to the left beyond the vertical guide pin 33 to a point nearer the eye H than such 40 guide pin, and thence back towards the other side as shown in Figs. 5 and 6, or it may not extend over to the guide pin as shown in Fig. 7.

I claim:

45 1. The combination in a shuttle for reverse wound bobbins having an eye on one side, a bobbin chamber, a threading chamber in continuation thereof which connects with the eye, and a delivery passage extending forward from the threading chamber; of a nose block fixed in the threading chamber on the eye side having a nose which extends forward of the eye and slopes down into the threading chamber, a thread guide 50 horn extending down and back below the nose, and a vertical thread guide pin behind said horn; with a thread directing guide plate so fixed in the threading chamber on the opposite side from the eye as to slope down 55 thereinto in the direction of the unwinding yarn under the nose of the nose block, and a thread retaining guide hook which extends from and under the back part of the thread directing guide plate proximate the bobbin chamber in the direction of the unwinding 60 yarn.

65 2. The combination in a shuttle having an

rection of the unwinding yarn to a point nearer the eye than the vertical guide pin, and thence back towards the other side.

2. The combination in a shuttle for reverse wound bobbins having an eye on one side, a bobbin chamber, a threading chamber in continuation thereof which connects with the eye, and a delivery passage extending forward from the threading chamber; of a nose block fixed in the threading chamber on the eye side having a nose which extends forward of the eye and slopes down into the threading chamber, a thread guide horn extending down and back below the nose, and a vertical thread guide pin behind said horn; with a thread directing guide plate so fixed in the threading chamber on the opposite side from the eye as to slope down thereinto in the direction of the unwinding yarn under the nose of the nose block, and a thread retaining guide hook which extends from and under the back part of the thread directing guide plate proximate the bobbin chamber in the direction of the unwinding 85 yarn in such position as to overlap a part of the shuttle.

3. The combination in a shuttle for reverse wound bobbins having an eye on one side, a bobbin chamber, a threading chamber in continuation thereof which connects with the eye, and a delivery passage extending forward from the threading chamber; of a nose block fixed in the threading chamber on the eye side having a nose which extends forward of the eye and slopes down into the threading chamber, a thread guide horn extending down and back below the nose, and a vertical thread guide pin behind said horn; with a thread directing guide plate so fixed in the threading chamber on the opposite side from the eye as to slope down 95 thereinto in the direction of the unwinding yarn under the nose of the nose block, and a thread retaining guide hook which extends from and under the back part of the thread directing guide plate proximate the bobbin chamber in the direction of the unwinding 100 yarn.

4. The combination in a shuttle having an eye, a bobbin chamber and a threading chamber in continuation thereof which connects with the eye; of a guide plate so fixed to the side of the threading chamber opposite the eye as to extend slopingly down into the threading chamber, and a hook guide in extension thereof on the back end proximate the bobbin chamber; with a nose block on the side of the threading chamber next the guide eye which has a nose extending forward of the guide eye and over the guide plate and a vertical thread pin so positioned that it is axially inside said guide hook.

5. The combination in a shuttle having an

eye, a bobbin chamber and a threading chamber in continuation thereof which connects with the eye; of a guide plate so fixed to the side of the threading chamber opposite the eye as to extend slopingly down into the threading chamber and a hook guide in extension thereof; with a nose block on the side of the threading chamber next the guide eye which has a nose extending forward of the guide eye and over the guide plate and a vertical thread pin.

6. The combination in a shuttle having an eye, a bobbin chamber and a threading

chamber in continuation thereof which connects with the eye; of a guide plate so fixed to the side of the threading chamber opposite the eye as to extend slopingly down into the threading chamber and a hook guide in extension thereof; with a nose block on the side of the threading chamber next the guide eye which has a nose extending forward of the guide eye thence down and back towards and over the guide plate and having at the back a stop hook and a vertical thread pin.

ISAAC SNOW.
